COMBINATION LOCK

Oscar Lalonde, Bronx, N. Y.

Application March 11, 1941, Serial No. 382,704

9 Claims. (Cl. 70—74)

This invention relates to locks that may be opened either by a key or permutation mechanism, and while the invention is capable of general use, it is particularly adapted for embodiment in locks for service kits, brief cases, lock boxes or the like.

The principal object of the invention is to provide a lock that may be opened either by a key or by permutation mechanism and which is extremely compact, inexpensive to manufacture and has an improved construction, arrangement and co-operation of parts such as to enable certain of the same to be employed in both the key and permutation lock opening operations.

Another object of the invention is to provide a lock that may be opened either by a key or by permutation mechanism and which, through unsetting of the permutation mechanism and provision of a device for unsetting key controlled tumbler plates, prevents opening of the lock except by one having a proper key and knowledge of the proper combination of numbers for setting said permutation mechanism.

Another object of the invention is to provide a lock that may be opened either by a key or by permutation mechanism, and which, through the provision of key controlled tumbler plate unsetting means, does not have to be locked by the key after employment thereof to open said lock.

Another object of the invention is to provide a lock that may be opened either by a key or by permutation mechanism and which has a generally improved and efficient construction of parts and a compact and fool-proof arrangement thereof as to render the lock particularly useful upon service kits, brief cases, lock boxes, or the like.

Another object of the invention is to provide an improved permutation or combination lock which, by reason of several different dial setting marks thereon, renders it impossible for an unauthorized person to learn by observation which mark and particular combination of dial members are employed to open the lock.

Another object of the invention is to provide an improved permutation or combination lock which, through several different dial setting marks thereon, enables a considerably increased number of lock opening number combinations to be employed.

The invention consists of the construction, combination and arrangement of parts, as herein illustrated, described and claimed.

In the accompanying drawings, forming part hereof, is illustrated one form of embodiment of

the invention, in which drawings similar reference characters designate corresponding parts, and in which:

Figure 1 is a perspective view of a lock embodying the invention and shown installed upon a service kit;

Figure 2 is an enlarged front elevation of the lock with a cover plate and associated parts removed and a bolt shown locked by key controlled tumbler plates;

Figure 3 is a view similar to Figure 2, but showing the bolt unlocked through setting of the tumbler plates by a key;

Figure 4 is a view similar to Figure 3 but showing the tumbler plates unset and the bolt unlocked by permutation mechanism;

Figure 5 is a longitudinal sectional view on the line 5—5 of Figure 2, looking in the direction indicated by the arrows and showing the cover plate and associated parts omitted in Figures 2, 3 and 4;

Figures 6 and 7 are transverse, sectional views on the lines 6—6 and 7—7, respectively, of Figures 2 and 3, looking in the directions indicated by the arrows and showing the cover plate;

Figure 8 is a detailed exploded perspective view of an assembly of parts including a lock casing, a bolt, a spring, a bolt operating device, and permutation mechanism; and,

Figure 9 is a detailed exploded perspective view of an assembly of parts including tumbler plates, a retaining spring therefor, and tumbler plate unsetting means.

Referring to the drawings, and more particularly to Figure 1 thereof, 10 indicates a front portion of a service kit and 11 indicates a similar portion of a hinged cover for said kit. The cover 11 has secured thereto, as by rivets 12, a hasp plate 13 on which is hinged, as at 14, a hasp 15. The hasp 15 is provided with a keeper 16 (Figure 5) which, when the cover 11 is closed and the hasp 15 is swung toward and away from the front of the service kit 10, passes into and out of a keeper opening 17 in a cover plate 18 for a lock casing 19. The lock casing 19 is provided with lugs 20 that are press fitted in suitable openings formed in the cover plate 18 and one of which is indicated at 21 in Figure 1 of the drawings. In this manner, the lock casing 19 is attached to the cover plate 18 interiorly thereof and after the various parts of lock mechanism, hereinafter described, have been assembled in said lock casing. Thereupon, the cover plate 18 is secured, as by rivets 22, to the front portion of the service kit 10 in position such that when the hasp 15 is

swung into and out of engagement with the cover plate 18 the keeper 16 will pass into and out of said plate through the keeper opening 17 therein.

Slidably arranged in the casing 19 is a bolt operating device 23 having a bolt engaging lug 24 at one end, and spaced lugs 25 at the opposite end for a purpose hereinafter set forth. The bolt operating device 23 is provided at opposite sides thereof with extensions 26 and 27 that engage opposite sides of the casing 19 to guide said device therein. The bolt operating device 23 also serves as a carrier for permutation mechanism hereinafter described, and for this purpose said device has fixed on it a post 28. The casing 19 is provided in one end thereof with a bolt opening 29, and slidably mounted in said opening is a bolt 30 which extends in said casing over the bolt operating device 23 and is movable with and relative thereto.

The bolt 30 has a beveled end 31 normally projecting outwardly through the opening 29 and faced toward the keeper opening 17 so as to be engaged with the keeper 16 to close the lock and disengaged from said keeper to open the lock. The bolt 30 has an arm 32, and the bolt engaging lug 24 of the bolt operating device 23 extends between the lock casing 19 and the arm 32 to engage said arm. The arm 32 has an upwardly and inwardly curved arm 33, the free end of which is provided with a detent 34. A spring 35 is mounted, as by a coil 36 thereof, on a lug 37 on the lock casing 19 and projecting within the same. A bent end 38 of the spring 35 bears against the bolt 30 and the opposite end 39 of said spring bears against one side of the lock casing 19. The spring 35 thus serves to normally maintain the bolt operating device 23 and the bolt 30 at the left hand end of the casing 19 (Figure 2) and to normally project the beveled end 31 of the bolt 30 outwardly through the bolt opening 29 for snap action engagement of said beveled end with the keeper 16 of the hasp 15.

The bolt operating device 23, as stated above, serves as a carrier for permutation mechanism, that comprises parts which are preferably arranged and constructed as follows: A washer 40, having a central opening 41 to receive the post 28 is fitted thereon against the device 23 and keyed to said post by a flat portion 42 thereof which engages a similar portion 43 of the washer opening 41. A tumbler disk 44 having a central opening 45 to receive the post 28 is rotatably mounted thereon against the washer 40. This tumbler disk 44 has a lug 46 which projects from the side of the disk opposite that bearing against the washer 40. The tumbler disk 44 is provided at a predetermined point in its periphery, with a notch 47 forming a shoulder 48 for engagement by the bolt detent 34 and a cam 49 for engagement by a rounded end 50 of said detent.

A washer 51, having a central opening 52 to receive the post 28, is fitted thereon against the tumbler disk 44 and keyed to said post by its flat portion 42 and engagement therewith of a similar portion 53 formed in the washer opening 52. A tumbler disk 54, having a central opening 55 to receive the post 28, is rotatably mounted thereon against the washer 51. This tumbler disk 54 is provided with diametrically opposed arcuate shaped slots 56 and 57, the tumbler disks 44 and 54 being interengaged through the medium of the lug 46 which extends from the disk 44 into the slot 56 of the disk 54. The tumbler

disk 54 is provided at a predetermined point in its periphery with a notch 58 forming a shoulder 59 for engagement by the bolt detent 34 and a cam 60 for engagement by the rounded end 50 of said detent.

A washer 61, having a central opening 62 to receive the post 28, is fitted thereon against the tumbler disk 54 and keyed to said post by the flat portion 42 thereof which engages a similar portion 63 formed in the washer at the central opening 62 thereof. A tumbler disk 64 is provided with a central opening 65 to receive the hub 66 of a dial 67 disposed exteriorly of the cover plate 18 for rotary and sliding movement relative thereto. The dial 67 and its hub 66 are provided centrally thereof with an opening 68 to receive the post 28 upon which said dial is rotatably mounted. The hub 66 of the dial 67 projects into the casing 19 through a slot 69 in the cover plate 18 that extends longitudinally thereof and enables said dial, under certain conditions, to be rotated to set or unset the permutation mechanism, and under other conditions, enables the dial to be reciprocated on the cover plate 18 to impart like movement to the bolt operating device 23.

The tumbler disk 64 is fixed on the dial hub 66 within the casing 19 and thus is rotatable by the dial 67 and serves to maintain it in position on the cover plate 18. The dial hub 66 and the tumbler disk 64 bear against the washer 61, and said disk and the tumbler disk 54 are inter-engaged, as by a lug 70 on the tumbler disk 64 and extending in the arcuate slot 57 of the tumbler disk 54. The tumbler disk 64 is provided at a predetermined point in its periphery with a notch 71 forming a shoulder 72 for engagement by the detent 34 and a cam 73 for engagement by the rounded end 50 of said detent.

The dial 67 is provided with an annular knurled knob 74 for manipulating it and said dial is also provided with an annular beveled portion 75 having a graduated scale and numbers herein disclosed as including the series 0 to 9. In accordance with the invention, a plurality of spaced dial setting marks, herein shown as three, are provided to prevent unauthorized visual observation of the proper combination of said numbers employed to open the lock. These marks are indicated at 76, 77 and 78, and they are applied on the cover plate 18 opposite the annular beveled portion 75 of the dial 67. In the particular lock herein disclosed, the mark employed is the lefthand one indicated at 76, and in opening the lock by the permutation mechanism, the dial is turned clockwise (Figure 1) to bring the number 2 opposite the mark 76, then counter-clockwise to bring the number 6 opposite said mark, whereupon said dial is turned clockwise to open the lock, all as hereinafter described. The three marks 76, 77, 78, not only prevent unauthorized visual observation of the lock opening combination of numbers, but also provide for three times as many different lock opening combinations of numbers employable in conjunction with the three marks 76, 77 and 78, selectively.

A lock embodying the invention is controlled for purposes of opening it by permutation mechanism constructed and arranged as described, or by key controlled tumbler plate mechanism comprised by parts preferably arranged and constructed as follows. The key controlled tumbler plate mechanism is arranged in the lock casing 19 between the bolt operating device 23 and the end of said casing opposite that in which the

bolt 30 is mounted. For this purpose, said opposite end of the casing 19 is provided in the bottom wall thereof with an opening 79 for reception of the shouldered end of a key 80. The key 80 is provided at a predetermined point on one side thereof with a tumbler plate actuating lug 81, and on the opposite side at predetermined points with spaced tumbler plate actuating lugs 82 and 83. The cover plate 18 is provided with a key opening 84 aligned with the opening 79, and the side walls of the casing 19 adjacent the end thereof opposite that in which the bolt 30 is mounted, are provided with tumbler plate retaining and guiding openings 85.

Arranged in the lock casing 19 is a leaf spring 86 having an arcuate shaped depression 87 to afford clearance for the key 80, and outwardly bent end portions 88 terminating in lugs 89 disposed in the openings 85 and whereby said spring is retained in proper position in the casing 19. A series of tumbler plates 90, 91, 92 are slidably arranged one against another in the casing 19 between the bolt operating device 23 and the end of the casing 19 opposite that in which the bolt 30 is mounted. These tumbler plates are relatively shiftable transversely of the bolt operating device 23 to set or unset them, and said plates have lugs 93 extending in the tumbler plate receiving and guiding openings 85. The tumbler plates 90, 91, 92 are disposed between the cover plate 18 and the spring 86 and said spring prevents accidental relative displacement of said plates.

The tumbler plates 90, 91, 92 are aligned with the key openings 79 and 84 and are provided opposite thereto with openings 94, 95, 96 for reception of the key 80. In their corresponding inner edges, and at different predetermined points therealong, the tumbler plates 90, 91, 92 are provided with pairs of lug receiving slots 97, 98, 99 aligned with each other and with the lugs 25 of the bolt operating device 23 when the tumbler plates are set, and disaligned relative to each other and to said lugs 25 when said plates are unset. The tumbler plates 90, 91, 92 may be set by the key 80 as hereinafter described and, in accordance with the invention, said plates may be unset by means associated therewith.

Accordingly, the tumbler plates 90, 91, 92 are provided in their corresponding outer edges with recesses 100, 101, 102, and extending outwardly from said plates at opposite ends of said recesses, are pairs of lugs 103 and 104, 105 and 106, and 107 and 108. Slidably arranged in the casing 19 between the tumbler plates 90, 91, 92 and the adjacent end wall of said casing, is a tumbler plate unsetting device 109 having an operating lug 110 disposed in the recesses 100, 101, 102 between the pairs of lugs 103 and 104, 105 and 106, and 107 and 108 and extending outwardly of the cover plate 18 through the adjacent opening 21 (Figure 1) therein.

In the operation of the lock it will first be assumed that the tumbler plates 90, 91, 92 are unset and that it is desired to set them with the key 80 in order to open the lock. When the tumbler plates are unset, as presently described, their pairs of recesses 97, 98, 99 are disaligned relative to each other and to the lugs 25 of the bolt operating device 23, and the lock parts are locked and positioned as shown in Figures 2, 5 and 6 of the drawings. The tumbler plates 90, 91, 92 thus prevent actuation of the bolt operating device 23 and operation of the bolt 30 thereby to open the lock. When the key 80 is inserted through open-

ing 84 into openings 94, 95, 96 and 79, and turned in the proper direction, the key lug 81 will shift the tumbler plate 91 downwardly and the key lugs 82 and 83 will shift the tumbler plates 90 and 92 upwardly, as viewed in Figures 3 and 7 of the drawings. The tumbler plates 90, 91, 92 will thus be set with their pairs of recesses 97, 98, 99 in alignment with each other and with the lugs 25 of the bolt operating device 23. Thereupon, by moving the dial 67 to the right longitudinally of the recess 69 in the cover plate 18, corresponding movement will be imparted to the permutation mechanism, the bolt operating device 23 and the bolt 30. When the bolt operating device 23 is moved to the right, its lugs 25 enter the aligned pairs of tumbler plate recesses 97, 98, 99, the spring 35 is compressed, and the beveled end 31 of the bolt 30 disengaged from the keeper 16 of the hasp 15. The parts are thus positioned as shown in Figures 3 and 7 of the drawings, and the lock is unlocked. Thereupon the hasp 15 may be manually or spring actuated outwardly, and the cover 11 opened to open the service kit 10.

After the lock and the service kit have been unlocked and opened, respectively, as above described, the dial 67 is released and the spring 35 returns the bolt operating device 23 and the bolt 30 to the left, as viewed in Figures 2 and 5 of the drawings, so that the beveled end 31 of said bolt is projected through the opening 29. Thereupon the cover 11 of the service kit 10 may be closed and the hasp 15 swung inwardly so that the keeper 16 is engaged with the beveled end 31 of the bolt 30 through a snap action thereof afforded by the spring 35. The lock is then locked by the tumbler plate unsetting means 109 through actuation of the same downwardly by its lug 110. This unsets the tumbler plates 90, 91, 92 so that their pairs of recesses 97, 98, 99 are disaligned with respect to each other and to the lugs 25 and lock opening movement of the bolt operating device 23 and the bolt 30 is prevented.

Assuming now that with the mechanism locked by the tumbler plates 90, 91, 92, the owner desires to unlock said mechanism but has forgotten or misplaced his key. Under these conditions the lock may be opened by the permutation mechanism in the following manner. The dial 67 is turned clockwise (Figure 1) to bring the numeral 2 thereof opposite the mark 76, whereupon the dial is turned counter-clockwise to bring the numeral 6 thereon opposite said mark. This, through interengagement of the tumbler disks 44, 54, 64 by the lugs 46 and 70 in the slots 56 and 57, rotates said disk relatively so that the notches 47 and 58 of the disks 44 and 54 are brought into alignment opposite the detent 34 on the bolt 30. Thereupon the dial 67 is again turned clockwise to likewise turn the tumbler disk 64 and bring its notch 71 into alignment with the notches 47 and 58 at which time the spring 35 swings the bolt 30 clockwise about the bottom of opening 29 as a fulcrum, as indicated in dotted lines in Figure 4 of the drawings, and the detent 34 enters the aligned tumbler disk notches 47, 58, 71.

The dial 67 is then further turned clockwise to further rotate the tumbler disks 44, 54, 64 in the same manner, and said disks, through such rotation thereof and engagement of their shoulders 48, 59, 72 with the detent 34, move the bolt 30 inwardly and relative to the then locked bolt operating device 23. Figure 4 of the drawings

shows in full lines the position of the bolt 30 and the permutation mechanism when the former has been moved into the lock casing 19 by said mechanism. Under these conditions, the beveled end 31 of the bolt 30 is disengaged from the keeper 16 of the hasp 15, thereby opening the lock so that the hasp 15 may be swung outwardly and the cover 11 raised to open the service kit 10.

When the lock is opened and the bolt 30 moved inwardly by the permutation mechanism, the spring 35 is compressed. After opening the service kit 10 by the permutation mechanism, as described, the dial 67 is released, whereupon the spring 35 projects the bolt 30 outwardly through opening 29 for snap action engagement with the keeper 16 when the cover 11 and the hasp 15 are closed, as previously described. Thereupon the dial 67 is turned to rotate and unset the tumbler disks 44, 54, 64, and as a result of such rotation of the disks their cams 49, 60 and 73 disengage the detent 34 from the disks, the notches 47, 58, 71 are moved out of alignment, and the mechanism is locked against opening operation. The lock may then again be opened by the permutation mechanism or by the key 80, as previously described, and in the latter case shifting of the tumbler plates 90, 91, 92 by the key 80 causes said plates to shift the tumbler plate unsetting means 109 upwardly into position for again unsetting the plates through downward movement of said device imparted thereto after the lock has been opened with the aid of the key 80, as described.

It will thus appear that the invention embodies a lock having a novel construction, arrangement and operation of parts, which lock may be opened either by a combination or a key and is particularly useful on service kits, brief cases, lock boxes, or the like. The lock herein disclosed has been illustrated and described with more or less particularity, but it is to be expressly understood that said lock constitutes one form of embodiment of the invention only and that said invention is not limited to said form of embodiment or otherwise than by the terms of the appended claims.

Having thus fully described the invention, what is claimed as new and desired to be secured by Letters Patent of the United States is:

1. In a lock of the type having a casing provided in one end thereof with a bolt opening, a cover plate for the casing provided with a keeper opening, a bolt in the casing slidably mounted in said bolt opening and normally projecting outwardly therethrough back of the cover plate and opposite its keeper opening, and a hinged keeper arranged to swing in and out of the cover plate through said keeper opening for engagement of the bolt with and disengagement of the same from said keeper, the combination of a bolt operating device engageable with the bolt and arranged for slidable actuation in the casing to shift the bolt and disengage it from the keeper, a plurality of tumbler plates slidably arranged one against another in the casing between said opposite end thereof and the bolt operating device, the tumbler plates being relatively shiftable transversely of the bolt operating device to set or unset them and the plates when set permitting actuation of the bolt operating device, when unset preventing actuation thereof, and permutation mechanism on the bolt operating device adapted for connection with the bolt to operate it when the tumbler plates are unset and actuation of said device is prevented, the permutation

mechanism having an operating dial therefor connected therewith through a slot in the cover plate and disposed exteriorly thereof, and said dial being manually operable to actuate said bolt operating device when said tumbler plates are set.

2. In a lock of the type having a casing provided in one end thereof with a bolt opening, a cover plate for the casing provided with a keeper opening and a key opening spaced therefrom, a bolt in the casing slidably mounted in said bolt opening and normally projecting outwardly therethrough back of the cover plate and opposite its keeper opening, and a hinged keeper arranged to swing in and out of the cover plate through said keeper opening for engagement of the bolt with and disengagement of the same from said keeper, the combination of a bolt operating device engageable with the bolt and arranged for slidable actuation in the casing to shift the bolt and disengage it from the keeper, and a plurality of tumbler plates slidably arranged one against another in the casing between said opposite end thereof and the bolt operating device, the tumbler plates being disposed opposite said key opening and adapted to be set by a key inserted therethrough, said tumbler plates being relatively shiftable transversely of the bolt operating device to set or unset them, the plates when set permitting actuation of the bolt operating device and when unset preventing actuation thereof, and means in the casing associated with the tumbler plates for unsetting the same, said tumbler plate unsetting means extending outwardly of the cover plate through an opening therein.

3. In a lock of the type having a casing provided in one end thereof with a bolt opening, a cover plate for the casing provided with a keeper opening and a key opening spaced therefrom, a bolt in the casing slidably mounted in said bolt opening and normally projecting outwardly therethrough back of the cover plate and opposite its keeper opening, and a hinged keeper arranged to swing in and out of the cover plate through said keeper opening for engagement of the bolt with and disengagement of the same from said keeper, the combination of a bolt operating device engageable with the bolt and arranged for slidable actuation in the casing to shift the bolt and disengage it from the keeper, a plurality of tumbler plates slidably arranged one against another in the casing between rear end thereof and the bolt operating device, the tumbler plates being disposed opposite said key opening and adapted to be set by a key inserted therethrough, said tumbler plates being relatively shiftable transversely of the bolt operating device to set or unset them and the plates when set permitting actuation of the bolt operating device and when unset preventing actuation thereof, permutation mechanism on the bolt operating device adapted for connection with the bolt to operate it when the tumbler plates are unset and actuation of said device is prevented, the permutation mechanism having an operating dial therefor connected therewith through a slot in the cover plate and disposed exteriorly thereof, said dial being manually operable to actuate said bolt operating device when said tumbler plates are set, and means in the casing associated with the tumbler plates for unsetting the same, said tumbler plate unsetting means extending outwardly of the cover plate through an opening therein and the tumbler plate unsetting means being manually movable in one

direction to unset the plates and movable in the opposite direction by said plates when they are set by said key.

4. In a lock having a casing provided in one end thereof with a bolt opening and a bolt slidably mounted in said opening and extending in the casing, the combination of a bolt operating device engaging the bolt and arranged for slideable actuation in the casing toward the opposite end thereof to operate said bolt, a plurality of tumbler plates slidably arranged one against another in the casing between said opposite end thereof and the bolt operating device, the tumbler plates being provided in different longitudinal portions along corresponding edges with slots and lugs at the opposite ends thereof, said tumbler plates being relatively shiftable transversely of the bolt operating device to set or unset them and the plates when set by a key permitting actuation of the bolt operating device and when unset preventing actuation of said bolt operating device, and means in the casing associated with the tumbler plates for unsetting them, said tumbler plate unsetting means having an operating device therefor extending in said slots and between said lugs.

5. In a lock, the combination with a casing having a bolt opening, of a bolt extending through the bolt opening into the casing and provided therein with a detent, interengageable rotatably mounted tumbler disks disposed in the casing opposite the detent and provided at different points in their peripheries with notches aligned with each other and the detent when the tumbler disks are set and disaligned when said disks are unset, spring means in the casing for swinging the bolt in said bolt opening and engaging the detent in the tumbler disk notches when the tumbler disks are set, and a dial for setting and unsetting the tumbler disks and for actuating them to operate the bolt thereby when the detent is engaged in the tumbler disk notches by said means.

6. In a lock, the combination of a bolt operating device having a bolt engaging lug, a bolt having an arm engageable by said lug and a curved arm extending from said first named arm, said bolt being operable by or relative to the bolt operating device and said curved arm being provided with a detent, tumbler plates adapted when set to permit operation of the bolt operating device and the bolt thereby and adapted when unset to prevent operation of said bolt operating device and the bolt thereby, permutation mechanism carried by the bolt operating device and positioned thereon opposite the curved arm of the bolt, said permutation mechanism including interengageable rotatably mounted tumbler disks provided at different points in their peripheries with notches aligned with each other and the detent when the tumbler disks are set and disaligned when said disks are unset, means for slightly swinging the bolt and engaging the detent in the tumbler disk notches when the tumbler disks are set, and a dial for setting and unsetting the tumbler disks and for actuating them to operate the bolt thereby relative to the bolt operating device when the detent is engaged in the tumbler disk notches by said means and operation of said bolt operating device is prevented by said tumbler plates.

7. In a lock, the combination of a bolt operating device, a bolt operable by or relative to the bolt operating device and provided with a detent, spring stressed tumbler plates adapted when set by a key to permit operation of the bolt operating device and the bolt thereby and adapted

when unset to prevent operation of said bolt operating device and the bolt thereby, a device associated with the tumbler plates for unsetting them, permutation mechanism carried by the bolt operating device, said permutation mechanism including interengageable rotatably mounted tumbler disks provided at different points in their peripheries with notches aligned with each other and the detent when the tumbler disks are set and disaligned when said disks are unset, means for engaging the detent in the tumbler disk notches when the tumbler disks are set, and a dial for setting and unsetting the tumbler disks and for actuating them to operate the bolt thereby relative to the bolt operating device when the detent is engaged in the tumbler disk notches by said means and operation of said bolt operating device is prevented by said tumbler plates.

8. In a lock, the combination of a bolt operating device having a bolt engaging lug, a bolt having an arm engageable by said lug and a curved arm extending from said first named arm, said bolt being operable by or relative to the bolt operating device and said curved arm being provided with a detent, tumbler plates adapted when set by a key to permit operation of the bolt operating device and the bolt thereby and adapted when unset to prevent operation of said bolt operating device and the bolt thereby, a device associated with the tumbler disks for unsetting them, permutation mechanism carried by the bolt operating device and positioned thereon opposite the curved arm of the bolt, said permutation mechanism including interengageable rotatably mounted tumbler disks provided at different points in their peripheries with notches aligned with each other and the detent when the tumbler disks are set and disaligned when said disks are unset, means for slightly swinging the bolt and engaging the detent in the tumbler disk notches when the tumbler disks are set, and a dial for setting and unsetting the tumbler disks and for actuating them to operate the bolt thereby relative to the bolt operating device when the detent is engaged in the tumbler disk notches by said means and operation of said bolt operating device is prevented by said tumbler plates, said dial being operable to move the permutation mechanism and the bolt operating device and operate the bolt thereby when said tumbler plates are set by said key.

9. In a lock, the combination of a bolt operating device, a bolt operable by said device, a curved stem on said bolt provided with a detent, a plurality of transverse tumbler plates adapted when set to permit operation of said device and when unset to prevent operation of the device and the bolt, permutation mechanism carried by the bolt operating device, said mechanism including interengageable substantially circular tumbler disks provided at different points in their peripheries with notches aligned with said detent when the disks are set and disaligned when the disks are unset, washers fixed intermediate said disks whereby they are prevented from frictional contact one with another, means for engaging said detent in the notches of said disks when the disks are set, and a dial for setting and unsetting the disks and for actuating them to operate said bolt thereby relative to the bolt operating device when the detent is engaged in the disk notches by said means and operation of said device is prevented by said tumbler plates.
